DESIGN FOR A HOLDER FOR COSMETICS OR THE LIKE

Henri Sadacca, New York, N. Y., assignor to Tekero, Inc., New York, N. Y., a corporation of
New York

Application July 1, 1933. Serial No. 48,617

Term of patent 3½ years

To all whom it may concern:

Be it known that I, HENRI SADACCA, a citizen of the Republic of Spain, and a resident of the Bronx, in the city and State of New York, with post office address at 350 Fifth Avenue, in the borough of Manhattan, city and State of New York, have invented a new, original, and ornamental Design for Holders for Cosmetics or the like, of which the following is a specification, reference being had to the accompanying drawings, forming part hereof.

I claim:

The ornamental design for a holder for cosmetics or the like, as shown.

HENRI SADACCA.
